(57) **CLAIM**

The ornamental design for an expandable bread box, as shown and described.

DESCRIPTION

FIG. 1 is a front view of the expandable bread box showing our new design;

FIG. 2 is a back view of the expandable bread box shown in FIG. 1;

FIG. 3 is a right side view of the expandable bread box shown in FIG. 1;

FIG. 4 is a left side view of the expandable bread box shown in FIG. 1;

FIG. 5 is a top view of the expandable bread box shown in FIG. 1; and,

FIG. 6 is a bottom view of the expandable bread box shown in FIG. 1.

FIG. 7 is a top, front right side perspective view of the expandable bread box shown in FIG. 1;

FIG. 8 is a top, front right side perspective view of the expandable bread box shown in FIG. 1 shown contracted with its lids open; and,

FIG. 9 is a top, front right side perspective view of the expandable bread box shown in FIG. 1 shown expanded with its lids open.
